JOHN PLAYER, OF NORTON, ENGLAND.

Letters Patent No. 65,600, dated June 11, 1867; patented in England March 25, 1865.

IMPROVEMENT IN APPARATUS FOR HEATING THE BLAST FOR FURNACES USED IN SMELTING IRON, &c.

The Schedule referred to in these Letters Patent and making part of the same.

TO ALL WHOM IT MAY CONCERN:

Be it known that I, JOHN PLAYER, of Norton, near Stockton-on-Tees, in the county of Durham, in England, have invented new "Improvements in Furnaces or Apparatus for Heating the Blast for Furnaces used in Smelting Iron, and for other Furnaces;" and I do hereby declare that the following is a full and exact description thereof, reference being had to the accompanying drawings, and to the letters of reference marked thereon.

This invention has for its object improvements in furnaces or apparatus for heating the blast for furnaces used in smelting iron, and for other furnaces. Heretofore, when heating the blast for furnaces, the waste gases of blast furnaces have been employed; but by reason of the construction of the furnaces or apparatus employed when such gases have been before used, the heating of the system of pipes or passages through which the blast is forced has been very irregular, and this irregularity has been consequent on the flames of the ignited gases passing freely to the system of pipes or passages in which the heating of the blast takes place.

Now, according to the present invention, I arrange apparatus for heating the blast for furnaces in such manner that the combustion of the gases takes place in a separate chamber from that in which the system of pipes or passages in which the blast is heated is situated, and the chamber in which the system of pipes or passages is situated is, by preference, above the combustion-chamber, and only communicates therewith by means of numerous openings through the top of the combustion-chamber. The upper chamber is of large dimensions as compared with the space occupied therein by the system of pipes or passages in which the heating of the blast takes place, so that such upper chamber is at all times pervaded by a red-hot atmosphere, which acts on all parts of the system of pipes or passages alike, and thus not only is a very highly heated blast maintained, but its heat is more constant and uniform than has heretofore resulted when using the waste gases of blast furnaces in heating systems of pipes or passages through which the blast passes and is heated.

Having thus stated the nature of my invention, I will proceed more fully to describe the manner of performing the same.

Description of the Drawings,

Which represent a double air-heating stove, constructed according to my invention, each stove being of a size suitable for heating about two thousand three hundred cubic feet of air per minute, at a pressure of two and a half pounds on the square inch, and to a temperature of about 1,200° Fahrenheit. The dimensions and arrangements shown in the drawings may be varied. The nature of each of the figures shown by the drawings being written thereon, it will not be necessary to repeat the same here.

A is the combustion-chamber, into which the waste gases are received and are burned, with an admixture of atmospheric air, as is well understood. The ignited gases ascend through the openings in the upper parts of the chamber A into the chamber B, where there will be no indication of flame, but a uniformly highly-heated vapor or fume. The pipes for heating the blast are arranged in the chamber B, as is shown, or otherwise, according to the judgment of the engineer constructing the apparatus. In the arrangement shown the atmospheric air to be heated enters the longitudinal mains D D, and passes therefrom through the series of pipes c c to the other or outlet main.

Having thus described the nature of my invention, and the manner of performing the same, I would have it understood that what I claim is—

The constructing or arranging of a hot-blast stove in the manner herein described, whereby the waste gases are ignited and consumed in a chamber separate from the chamber within which the pipes are contained.

JOHN PLAYER.
